LOCKING KEY RETAINER

Arnold J. Fleming, Ithaca, N. Y.

Application December 19, 1952, Serial No. 326,946

1 Claim. (Cl. 70—430)

1

The ordinary household key and lock usually found in doors can be made a very effective means for preventing entry so long as it remains in place. However, a common trick known to thieves and burglars is to use a tool inserted into the key-hole from the outside by which the key in the lock can be turned. Using such a tool the burglar can then readily open the ordinary door, either by turning the key to unlock it or by turning the key enough to push it out and open the door with another key.

In order to prevent such entry, various key fasteners or guards have been developed in the past embodying hooks or rings fitting around the shaft of the door knob and having depending elements which can project thru the loop or handle of the ordinary household key so that it cannot be turned as long as the securing device is in place.

The present invention is an improved retainer of that general type. The principal defects of previous retainers have been that they were unduly complicated and expensive, and that they could be displaced by a burglar using a wire or by shaking the key itself. The principal object of the present invention is to provide such a safety key retainer having a minimum number of parts that can be easily manufactured so as to reduce the cost, and yet provide a device which will effectively prevent a burglar from displacing it, so that the key will continue to be securely held in the safe position in the lock.

Referring now to the drawings forming part of this specification,

Fig. 1 is a front view of the retainer in the open position, showing the stem and hook, the rotatable lock, and the holding pins in the guiding slots.

Fig. 2 is a view of the same device turned around so as to show its back, with the rotatable lock closed around the shaft of a door knob, and the stem extending down thru the loop or handle of an ordinary key so as to prevent its turning.

Fig. 3 is a detail front view of the rotatable lock closure element.

Fig. 4 is a side elevation of the same.

Fig. 5 is a detail rear view of the hook element and its depending stem for holding a key in place.

Fig. 6 is a side view of the same.

Similar reference numerals refer to similar parts thruout the various views.

The hook element 1 of the device is best seen in Fig. 1, Fig. 5 and Fig. 6 and consists of a sheet metal stamping or other thin material made in the general shape of a question mark, having a

2

rounded head 2 and a depending stem 3 which terminates in a wedge shaped point 4. The head 2 has a slot or jaw 5 which slopes upward and is wide enough to slip over the shaft 6 of the door knob as shown in Fig. 2. The depending blade or stem 3 of the device hangs down and passes thru the loop of the handle 8 of the ordinary key in its key-hole 9. So long as the stem 3 is hooked on the door knob and projects thru the handle 8 of the key, the key cannot be rotated to any considerable extent and will remain in the locking position in the door.

However, it has been found that thieves have occasionally found a way to displace various devices of the key holding type by passing a wire or small rod thru the key hole to get it under the lower end of the depending stem and toss or force it up out of the loop of the key handle. To preclude such an action, the tip 4 of the stem

20 3 is not made square or broadly rounded, but is wedge shaped. This wedge shaped end not only assists in guiding the stem 3 thru the loop 8 of the key handle but also makes it difficult to raise the stem 3 by any wire or rod that may be used to try to lift it, since the lifter will not find a blunt surface to bear against but will tend to glance off in one direction or the other.

Another trick used by thieves is to unhook the element 1 from the door knob, either by shaking the knob or by other means. To prevent this, the present device has a rotary locking head 10 as shown in Fig. 1 and Fig. 2 and in separate detail in Fig. 3 and Fig. 4. This rotatable locking head 10 is made of a sheet metal stamping or other thin material in the general form shown in Fig. 3 and with a tab 11 projecting at right angles to serve as a handle, by which the head can be rotated. This head 10 has a slot 12 corresponding to the slot or jaw 5 of the hook element 1 so that when the slots 5 and 12 of the two elements are placed parallel the jaw is open, and when the head 10 is rotated about 90° the jaw is closed, and the opening left in the two elements is substantially a ring closely encircling the shaft

25 6 of the door knob. Fig. 1 shows the jaws open and Fig. 2 shows them closed around the door knob shaft 6.

The lock head 10 is guided in its rotary motion by arcuate slots 15 and 15' which may be cut in the head of the hook 1, and in these slots there travel pins 16 and 16' having overlapping heads 17 and 17', these pins 16 and 16' being held in the rotary lock head 10 by riveting or other suitable means as shown in Fig. 1 and Fig. 4. While 30 45 50 55 the arcuate slots 15 and 15' are shown in the

head 2 and the pins 16 and 16' are shown on the head 10, it will be understood that their positions could just as well be interchanged, with the slots in the rotary head 10 and the pins on the hook head 2, to produce the same effect. These arcuate guiding means insure the proper locking motion.

However, while the slots 15 and 15' are in general arcuate, they are provided with a special cam action at the end of the closing movement to force the pins 16 and 16' into terminal depressions 20 and 20', which act as detents to hold the movable member 10 securely at the end of its closing travel. The purpose of these detents is to hold the lock head closed against any shaking or rattling that might be used against it; in other words, to provide a definite resistance to unlocking the head which can only be done by considerable force applied properly to the tab 11.

In operation the door is first locked with the ordinary key left in the lock. Then the present device is opened and hooked on the door knob as shown in Fig. 2 with the stem 3 passing thru the loop of the handle of the door key. The rotary head 10 is then turned by means of the tab or handle 11 until the pins 16 and 16' snap down into the depressions 20 and 20' as shown in Fig. 2. This holds the device securely on the knob and thru the key handle so that it cannot be turned or shaken out. The whole device is light, durable and can be easily manufactured.

I claim:

A locking key retainer for preventing the removal of a door key comprising in combination a hook element having a head and stem and a general contour similar to that of a question

mark with an opening in one side of its head adapted to hook over the shaft of a door knob and a stem extending downward to pass thru the loop of a door key when a door is locked, said stem terminating in a downwardly extending point so that it cannot readily be lifted out of the loop by upward pressures, said hook element having a pair of concentric arcuate slots in its head on opposite sides of the opening, the upper end of the upper slot and the lower end of the lower slot each having a retaining notch extending downward toward the stem, a rotatable locking element having guiding pins in the arcuate slots of the hook so that it can rotate relative to said hook, said locking element having a slot which in one position accords with the opening in the head of the hook element and when the locking element is rotated closes said opening around the shaft of the door knob, and a handle on said locking element by which it may be rotated and by which the guiding pins may be moved into and out of the retaining notches at the ends of the slots, said notches extending downward toward the stem so that any attempt to lift stem out of the key loop will only force the guiding pins more securely into the retaining notches.
